UNITED STATES PATENT OFFICE.

AUREL SZENTE, OF VIENNA, AUSTRIA.

CLOCK FOR MOTOR CARS AND OTHER VEHICLES.

Application filed December 4, 1924, Serial No. 753,881, and in Austria December 10, 1923.

This invention relates to clocks for motor cars and other vehicles and consists in a clock combined with an electro-magnetic feeding mechanism, which operates in such a manner, that the clock-work remains wound up and the whole spring force is stored while the clock is connected with the electric current; the stored up force only becomes operative as soon as the current ceases to flow or is switched off. If the clock is shut off from current supply for a longer time than the stored spring power will last, the clock may be used as any other mechanical clock-work as long as necessary. It may be wound up in the usual way either by hand or by an electro-magnetic mechanism. As soon as the current is switched in again the clock will be operated as an electric clock the spring power being stored up as before. The accompanying drawings show by way of example an embodiment of the clock according to the invention. Fig. 1 illustrates the clock removed from the casing in rear view. Fig. 2 shows the feeding mechanism in a similar view the elements being in another position of their operation. Fig. 3 is a side view of the clock with a part of the casing and Fig. 4 shows a detail on a part of the dial.

1, 2 and 3 designate plates on which the winding arbor 4 is journaled, which has an extension passing through an opening 5 in the dial 6. A ratchet wheel 7 is rigidly fastened to said axle, whereas the armature 8 of a horseshoe magnet 9 is pivotally mounted thereon. The armature 8 carries at one end a bolt 18 over which a sleeve 17 is fitted having an arm 16 which carries a pin 15 projecting at right angles from the arm and engaging the ratchet wheel 7. The ratchet wheel is connected with the axle 13 of the clock spring 14 by means of a gearing 10, 11 and 12. The other end of the sleeve 17 carries an arm 19 arranged in parallel to arm 16, the arm 16 being pressed against the ratchet wheel 7 by the action of a spring 20 fastened to the bolt 18. The plate 1 carries a bolt 21 on which an arm 22 is pivotally mounted; a pin 23 on the front edge of said arm 22 acting as a detent is maintained by means of a tension spring 24 in engagement with the ratchet wheel 7 said spring being inserted between a bolt 25 on plate 1 and the arm 22. A second arm 26 to which a contact piece 27 is fastened is pivotally mounted on bolt 21; the contact piece 27 extends over a contact pin 19' of the arm 19. The arm 26 is connected with the bolt 25 by means of a tension spring 28 and with the arm 22 by means of a projection 29, a screw 31 on arm 22 extending through a slot 30 in said projection. On the plate 1 an arm 33 is fastened by means of a screw 32; a leaf spring 34 presses against said arm. The spring 34 is fastened on the upper face of the armature 8. The armature carries a pin 35 projecting to the rear (Fig. 3) to which is fastened one end of a spiral spring 36 having its other end fixed on a pin 37 which extends through plates 2 and 3. This spring tends to keep the armature in the circuit closing position shown in Fig. 1 or to bring it into this position, if moved. The current is supplied from the battery with which the vehicle is provided by means of a binding post 38 carried by the bolt 39 on plate 1. The current flows through plate 1, ratchet wheel 7 and pin 15 and from there if the pin 19' is in contact with the contact piece 27 to said contact piece. The current then passes through a conductor 41 to a coil 42 and through a second coil 43, spring 44 and a clamp 45 on the casing back to the battery. The arm 26 of the contact piece is insulated from the plate by means of two insulating washers 40.

The operation of the clock is the following: If the pin 19' is in the position shown in Fig. 1 it closes the circuit by means of the contact piece 27 and the horse-shoe magnet 9 moves the armature to the position illustrated in Fig. 2. At the same time the driving pawl pin 15 engages the next tooth of the ratchet wheel 7 the current being interrupted between pin 19' and contact piece 27; the action of the electro-magnet ceases and spring 36 brings back the armature into the position shown in Fig. 1 the pin 15 then turns the ratchet wheel 7 for one tooth in clockwise direction. This movement is transmitted by means of the gearing 10, 11 and 12 to the axle 13 of the clock spring 14 which is consequently gradually wound up. Pin 19' is returned to the position shown in Fig. 1 and the operation above described is repeated until the clock spring 14 is completely wound up. If pin 15 now engages the next tooth of the ratchet wheel and the action of the electro-magnet ceases the ratchet wheel under the action of spring 36

- can only turn as far as the clock spring runs down. It is then wound up again for one tooth breadth of the ratchet wheel by means of the electro-magnet.
5. Thus the whole spring power remains stored up while the clock is connected with the battery and will serve for operating the clock for some time—as a rule 24 to 30 hours —after the battery has been switched off.
10. If there is no current supply for a longer time than that the clockwork may be wound up by means of an ordinary watch key which will engage the square head 4' on the axle 4.
15. On the end of the winding arbor 4 which projects from the dial 6 a small hand 46 is provided which is turned round for a certain distance each time the ratchet wheel is stepped forward so that the driver of the 20 car is able to see, whenever he looks at the dial, whether the clock is worked electrical- ly or not.
- What I claim is:
1. The combination with a clock having a 25 winding mechanism including a manually operated winding arbor; of a ratchet wheel secured on said arbor, an electro-magnet, a spring-retracted armature therefor pivoted on said arbor, a pivoted, spring-urged driv- 30 ing pawl on said armature cooperating with said wheel, a parallel contact arm carried by said pawl and a contact engaged by said arm.
2. The combination with a clock having a 35 winding mechanism including a manually operated winding arbor; of a ratchet wheel secured on said arbor, an electro-magnet, a spring-retracted armature therefor pivoted on said arbor, a driving pawl for said wheel and a contact arm both mounted at one end 40 of said armature, a contact arranged for engagement by said arm and a detent for said
- wheel mounted adjacent the opposite end of said armature.
3. The combination with a clock having a 45 winding mechanism including a manually operated winding arbor; of a ratchet wheel secured to said arbor, an electro-magnet, an armature therefor pivoted on said arbor, a spring-urged driving pawl for said wheel pivoted on one end of said armature, a contact arm parallel to and movable with said pawl, a pivoted, spring-retracted detent for said wheel adjacent the opposite 50 end of the armature, a pivoted, spring-re- tracted contact arranged for engagement by said contact arm, and a pin and slot connec- 55 tion between said contact and detent to permit slight independent movement of said contact and thereby effect a wiping contact with the contact arbor.
4. The combination with a clock having a 60 winding mechanism including a manually operated winding arbor; of a ratchet wheel secured to said arbor, an electro-magnet, an armature therefor pivoted on said arbor, a 55 spring-urged driving pawl for said wheel pivoted on one end of said armature, a contact arm parallel to and movable with said pawl, a pivoted, spring-retracted detent for said wheel adjacent the opposite 70 end of the armature, a pivoted, spring-re- tracted contact arranged for engagement by said contact arm, a pin and slot connection between said contact and detent to permit slight independent movement of said contact and thereby effect a wiping contact with the contact arbor, and a leaf spring mounted on the armature.

In testimony that I claim the foregoing as my invention, I have signed my name.

AUREL SZENTE.
